Primary Examiner — Robert M Spear(74) *Attorney, Agent, or Firm* — Abel Law Group, LLP(57) **CLAIM**

The ornamental design for a chill rod, as shown and described.

DESCRIPTION

FIG. 1 is an isometric view of a chill rod showing our new design.

FIG. 2 is a side view thereof; and,

FIG. 3 is a top view thereof.

The present invention relates in general to devices for chilling liquids and, in particular, to a chill rod for improving the service of beverages.
